(57) **CLAIM**

The ornamental design for a mixing bowl, as shown and described.

DESCRIPTION

FIG. 1 is a perspective view of a mixing bowl according to the design;

FIG. 2 is a front elevation view thereof; a back elevation view showing no part of the claimed design;

FIG. 3 is a right side elevation view thereof, a left side elevation view being a mirror image of the view being shown in FIG. 3;

FIG. 4 is a top plan view of the design; and,

FIG. 5 is a bottom plan view thereof.

The portions of the article shown in broken line form no part of the claimed design.

1 Claim, 5 Drawing Sheets
